UNITED STATES PATENT OFFICE.

WILLIAM J. BRUNELL, OF DETROIT, MICHIGAN.

SKATE SHARPENER.

Application filed October 26, 1921. Serial No. 510,638.

To all whom it may concern:

Be it known that I, WILLIAM J. BRUNELL, a citizen of the United States, residing at Detroit, in the county of Wayne and State 5 of Michigan, have invented certain new and useful Improvements in Skate Sharpeners, of which the following is a specification.

This invention relates to skate sharpeners and more particularly to an improved 10 skate file and file holder adapted to be used for grinding and grooving the edges of skates.

The primary object of the invention is to provide a file which will be adapted to 15 sharpen the skates in a manner known as hollow grinding and grooving.

Other objects of the invention will appear upon consideration of the following detail 20 description and accompanying drawings, wherein:—

Figure 1 is a side elevation of the file, Fig. 2 is a cross-section on the line 2—2 of Fig. 1,

Fig. 3 is a side elevation of the file holder, Fig. 4 is a cross-section on the line 4—4 of Fig. 3, and

Fig. 5 is a cross-section showing the holder and file assembled for use.

Referring to the drawing by numerals, 30 the file 1 is substantially square in cross section and is provided on each face with filing surface 2. The longitudinal edges at diametrically opposite points are rounded as indicated at 3 while the opposite longitudinal edges are square as indicated at 4. This file may be of any desired length and is adapted to be mounted in a file holder 5 which consists of a tubular member 6, a longitudinal slot 7 extending throughout its 35 entire length and provided with longitudinal flanges 8 extending from the marginal edges of the slot, these flanges 8 being adapted to engage the opposite sides of the skate blade when the device is in use. Outwardly 40 turned ears 9 on the end of the flanges 8 are provided to form finger grips whereby the holder may be manipulated when it is in use.

In order that the file will be properly 45 held in the holder, both the file and the

holder are provided with bolt openings to receive the removable bolts 10 which are extended through the openings and fastened with nuts or other removable means.

When the file holder is in use, the file will 55 be placed within the tube 6 and one of the edges 3 turned so that it will be in alignment with the slot 7 whereupon the flanges 8 will be engaged with opposite sides of the 60 skate blade and the longitudinal slot will be reciprocated in the usual manner. The rounded edges 3 will hollow grind the edge of the skate and if the user desires a groove to be provided in the edge of the skate he may simply reverse the position of the file 65 in the holder by removing and rearranging the bolt 10 so that the lower edges 4 will be in a position to grind the edge of the skate. In this manner a perfectly ground skate 70 may be provided with either a hollow grind or a longitudinal groove.

Minor changes may be made in the details of construction without departing from the spirit of the invention or the scope of the claim hereunto appended.

What is claimed is:—

An implement of the character described comprising a file of any desired length substantially square in cross-section, two of its opposite marginal edges being rounded, the 80 other two longitudinal edges being square, a file holder comprising a tube adapted to receive the said file and provided with a longitudinal slot adapted to be aligned with one of the longitudinal edges of the said file, 85 the said tube being equipped with longitudinally extending flanges extending from the marginal edges of the said groove, means to removably hold the file within the tube whereby any one of the file edges may 90 be aligned with the said longitudinal groove, each longitudinal flange being equipped with a finger grip whereby the said tube may be manually moved when it is in use.

In testimony whereof, I have affixed my 95 signature in the presence of two witnesses.

WM. J. BRUNELL.
